UNITED STATES PATENT OFFICE.

JOHN D. WAGSTAFF, OF DALLAS, TEXAS.

DESIGN FOR A SHOW CASE.

Application filed November 2, 1923. Serial No. 7,654. Term of patent 14 years.

To all whom it may concern:

Be it known that I, JOHN D. WAGSTAFF, a citizen of the United States, residing at Dallas, in the county of Dallas and State of Texas, have invented a new, original, and ornamental Design for Show Case, of which the following is a specification, reference being had to the accompanying drawing, forming part thereof.

The figure is a perspective view of a show case, showing my new design.

I claim:

The ornamental design for a show case, as shown.

JOHN D. WAGSTAFF.
